UNITED STATES PATENT OFFICE.

ELTON D. KOHR, OF YORK, PENNSYLVANIA.

DESIGN FOR A DISPENSING BOOTH.

Application filed September 7, 1928. Serial No. 28,062. Term of patent 3½ years.

To all whom it may concern:

Be it known that I, ELTON D. KOHR, a citizen of the United States, residing at York, in the county of York and State of Pennsylvania, have invented a new, original, and ornamental Design for a Dispensing Booth, of which the following is a specification, reference being had to the accompanying drawing, forming a part hereof.

Figure 1 is a front elevation of a dispensing booth, showing my new design.

Figure 2 is a perspective view of a dispensing booth, showing my new design.

I claim:

The ornamental design for a dispensing booth, as shown.

ELTON D. KOHR.
